US0D1063817S

(12) **United States Design Patent** (10) Patent No.: **US D1,063,817 S**
(45) Date of Patent: ** Feb. 25, 2025

(54) **SOLAR PANEL**

- (71) Applicant: **Shenzhen Hello Tech Energy Co., Ltd.**, Shenzhen (CN)
- (72) Inventors: **Wei Bai**, Guangdong (CN); **Zhongwei Sun**, Guangdong (CN); **Anliang Peng**, Guangdong (CN); **Xiaowei Yin**, Guangdong (CN)
- (73) Assignee: **Shenzhen Hello Tech Energy Co., Ltd.**, Shenzhen (CN)
- (**) Term: **15 Years**

(21) Appl. No.: **35/518,861**

(22) Filed: **Jul. 17, 2023**

(80) **Hague Agreement Data**

- Int. Filing Date: **Jul. 17, 2023**
Int. Reg. No.: **DM/231123**
Int. Reg. Date: **Jul. 17, 2023**
Int. Reg. Pub. Date: **Nov. 3, 2023**

(30) **Foreign Application Priority Data**

- Jan. 17, 2023 (CN) 202330033221.9
Jun. 26, 2023 (CN) 202330393215.4
- (51) LOC (15) Cl. **13-02**

(57)

CLAIM

The ornamental design for a solar panel as shown and described.

DESCRIPTION

1. Solar panel
- 1.1: Perspective
- 1.2: Perspective
- 1.3: Front
- 1.4: Back
- 1.5: Left
- 1.6: Right
- 1.7: Top
- 1.8: Bottom

1 Claim, 8 Drawing Sheets
